UNITED STATES PATENT OFFICE.

FRANK OSCAR LEVI CHORLTON, OF BURY, ENGLAND.

VARIABLE-SPEED GOVERNOR.

Application filed July 21, 1925, Serial No. 45,138, and in Great Britain July 25, 1924.

The invention relates to a governor-ball type of governor operating against an external load or resistance applied through a lever device, which is capable of use in those cases where a considerable range of speed has to be provided for, as for example when the prime mover is employed for driving a rolling mill, or for driving a paper making machine.

10 In these instances, it is desirable, as in ordinary types of governors, for any particular speed to be maintained for the time being, with very little deviation, however the load upon the prime mover may alter 15 within known limits.

The invention consists in combining a lever device with a variable fulcrum thereat whereby the applied load in the form of a spring, upon the governor, is capable of being altered at will, to conform to the conditions of the governor for an altered speed, with a device which is arranged to vary the 20 radial distance of the governor balls in addition. As, in the double event, the resulting speed of the governor changes at a different rate for the two operations named, it becomes possible to adjust the mechanism used whereby the desired conditions are attained.

With reference to the accompanying drawings, Fig. 1 is a sectional elevation of a high speed governor, suitable for being driven from a prime mover, provided with means according to my invention for varying an applied spring load thereon, and at the same 30 time, altering the distance of the governor balls apart to suit. Fig. 2 is a section through line 2—2 of a detail in Fig. 1, some parts being left in elevation.

a is a fixed casing in connection with the 40 engine frame, not shown, but which casing is by no means necessary. *b* is the governor spindle which is assumed to be driven from the prime mover in any well known manner. *c* is a cross bar attached to spindle *b*, and 45 pivoted or fulcrumed at *d* is an ordinary bell-crank lever *e*, in each case, carrying attached governor ball *h*. *k* is a loose sleeve upon spindle *b* as is well understood, and which is in link connection shown with the levers *e*. A non-rotating collar within a 50 groove in *k* is indicated at *p*.

As illustrated, the lever device *n* pivoted at one end by a pin *m* to the collar *p*, the hole in said collar for *m* being assumed sufficiently larger to allow the requisite vertical movement of the end concerned of the lever

n taking place when the governor is in action, and at the other at *o* to a spindle *r*, is provided with an adjustable fulcrum as at *l*, which in the present instance consists of a 60 revoluble pin attached to trough-shaped slides *t* which partly envelop a pair of levers *n* described, there being here one on each side of collar *p*.

The parts *t* are capable of being moved 65 along the length of lever *n* or are here mounted upon a piece or cross-head *u*, extended lower portions of which are engaged by guides *v* projecting from casing *a*. A lug or projection *w* from *u* is screw-threaded 70 so as to be engaged by an inclined screw-threaded spindle *x* passing through the same. Said spindle *x* is capable of being operated or turned by attached wheel *y*.

s is the usual or common spring device for 75 supplying the applied load to the governor, which is arranged to be initially compressed to a degree suitable by means indicated.

It will be seen that on the turning of the spindle *x* the position of pin or fulcrum *l* 80 is altered along the length of the lever *n*, and that on account of said pin *l* being also moved more or less in a vertical direction due to the inclination of mount for said spindle *x*, the sleeve *k* and therefore levers *e* 85 are operated, with the result that the radial distance of the balls *h* relative to the axis of *b* is increased or decreased as the case may be.

By adjustment of these two factors, the 90 desired conditions may be attained as already described.

The spindle device *x* is merely shown as a convenient means for moving the fulcrum block *t* along a plane inclined to the lever *n*, 95 which movement is the one to be attained in the bringing about of the result described.

A portion only of the governor movement in each and every position is utilized to give a sufficient movement to control the mechanism as is necessary for complete control of the prime mover, or mechanism the governing of which is desired.

The arrangement illustrated brings about 105 the condition that the mean working tension of the spring *s* is constant for the range of speeds for which the governor is designed. This becomes possible by reason of the facts that the higher the speed of mechanism to be controlled, the nearer together the balls *h* 110 are brought by the operation of the downwardly inclined screw spindle *x*, and vice

versa, and the ratio of lengths into which the lever n is divided by the fulcrum l is arranged to be such, that the pressure at the governor end of said lever is inversely proportional to said ratio.

I claim:—

In a variable-speed governor of the governor-weight type, and for controlling mechanism related to a prime mover, a 10 spring loaded lever connected at one end to the spring forming said load, and at the other end to a movable part of the governor for controlling the radial distance of the governor weights referred to, a reduction 15 of radial distance aforesaid corresponding to an increase of speed, and vice versa, a

fulcrum piece slidably mounted on said lever for being moved along a plane inclined to said lever, a hand controlled device for so moving the fulcrum piece, said fulcrum capable of dividing the lever aforesaid into lengths the ratio of which is such that the pressure at the governor end of said lever is inversely proportional to said ratio, resulting in the mean working tension of the 25 spring load remaining constant for all working positions of the governor, substantially as herein set forth.

In testimony whereof I have affixed my signature.

FRANK OSCAR LEVI CHORLTON.
